UNITED STATES PATENT OFFICE.

LESTER KYLE ALDRICH, OF SIDNEY, OHIO.

CONVERTIBLE SINGLE OR DOUBLE ROTARY FEEDER.

Application filed October 14, 1927. Serial No. 226,222.

The invention relates to a convertible single or double rotary feeder and is an improvement on the convertible oscillating rotary feeder forming the subject matter of 5 patents numbered 1,664,960 and 1,664,961 granted to me April 3, 1928, which contain claims covering the various features of the machine disclosed but not claimed in the present application.

10 The object of the present invention is to improve the construction of the rotary feeding means disclosed in the aforesaid applications and to provide a simple, practical and comparatively inexpensive construction 15 adapted to double the production of the rotary feeder when running smaller sheets by enabling two sheets to be fed during each complete revolution of the suction nozzle.

A further object of the invention is to 20 provide simple, practical and efficient means for enabling the machine to be readily arranged for either feeding a single sheet during each complete revolution of the suction nozzle or two sheets during each revolution of the said nozzle.

With these and other objects in view, the invention consists in the construction and novel combination and arrangement of parts hereinafter fully described, illustrated 30 in the accompanying drawings and pointed out in the claims hereto appended, it being understood that various changes in the form, proportion and minor details of construction, within the scope of the claims, 35 may be resorted to without departing from the spirit or sacrificing any of the advantages of the invention.

In the drawings:-

Figure 1 is a side elevation of a rotary 40 feeder constructed in accordance with this invention.

Fig. 2 is a similar view showing the opposite side of the machine.

Fig. 3 is a plan view of the same.

Fig. 4 is an enlarged detail longitudinal 45 section view of the upper portion of the machine, the single cam being arranged for operating the machine to feed a single sheet during each revolution of the suction nozzle.

50 Fig. 5 is a similar view showing the double cam arranged for operating the suction nozzle to feed two sheets during each revolution of the same.

Fig. 6 is an enlarged plan view of a por-

tion of the machine, the double cam being in 55 operative position.

Fig. 7 is a detail plan view of a portion of the machine showing the single cam in operative position.

Fig. 8 is an enlarged detail sectional view 60 of the air valve.

Fig. 9 is a side view of the double pull off nozzle.

Fig. 10 is a transverse sectional view of 65 the same illustrating the arrangement of the L-shaped air ports and the T-shaped air ports.

Fig. 11 is a detail view of the closure plate 70 for covering the lateral vent orifices of the T-shaped air ports.

Fig. 12 is a detail view of one of the winding arms.

In the accompanying drawings in which is illustrated the preferred embodiment of the invention the convertible rotary feeder 75 comprises in its construction a double pull off nozzle 1 consisting of a continuously rotated disk suitably fixed to a rotary shaft 2 journaled in suitable bearings and the sides of the frame 3 of the machine and provided 80 at one portion of its periphery with an arcuate series of suction mouths 4 and at the diametrically opposite portion of its periphery with an arcuate series of suction mouths 4^a for successively operating on the 85 uppermost sheet 5 of a stack to pull the sheet off the stack and carry the same to a pull off roll 6 and rubber covered spools 7 arranged above the pull off roll 6 and cooperating with the same to complete the feeding 90 operation and carry the sheet into the machine with which the automatic feeder is associated. The suction mouths 4 and 4^a are arranged in two sets or series which are adapted to be successively operated during 95 each revolution of the double suction nozzle when running smaller sheets and the suction mouths 4^a as hereinafter fully explained are

adapted to be rendered inoperative to permit only the operation of the suction mouths 4 to feed a single sheet from the stack during each revolution of the double suction nozzle when running on large sheets. The suction mouths 4 are arranged at regular intervals and are connected by passages or ducts 8 100 and with lateral ports 9 which are adapted to be brought successively into register with an outlet or aperture of an air passage 105 10

of an air arm 11. The air ports are formed by the suction mouths, the passages or ducts 8 and the lateral ports 9 are approximately L-shaped.

- 5 The suction mouths 4^a are arranged at regular intervals and are connected by passages or ducts 8^a with lateral ports 9^a which are adapted to be brought successively into register with the outlet or aperture of the 10 air passage 10 of the air arm 11. The suction mouths 4^a are also provided at the inner ends of the passages or ducts 8 with lateral outlets of vents 9^b which are covered by a closure plate 9^c when the suction mouths 15 4^a are operated and the suction nozzle is acting as a double suction nozzle for feeding two sheets during each revolution of the nozzle. The closure plate 9^c is pivotally and detachably secured to the suction nozzle 20 by a screw 9^d threaded into the suction nozzle and adapted to either pivotally or detachably secure the closure plate 9^c in position for covering and closing the lateral 25 vents or outlets 9^b. The closure plate 9^c is adapted to be firmly secured in position for closing the vents or outlets 9^b and it is also adapted to be removed for exposing the vents or outlets 9^b to the atmosphere to prevent the operation of the suction mouths 4^a. 30
- 30 When the closure plate 9^c is in position it is firmly held therein by the clamping screw 9^d and it will permit the opening and closing of the vents or outlets 9^b without removing the closure plate from the suction nozzle. 35
- 35 If desired, the closure plate may be entirely removed from the suction nozzle and any number of fastening devices may, of course, be employed for securing the closure plate in its closed position. When the closure plate 40 is in its closed position the pull off nozzle is adapted for feeding two sheets during each revolution and when the closure plate is removed to expose the vents or outlets 9^b the suction nozzle is adapted for feeding a 45 single sheet during each complete revolution of the said nozzle.

The pull off nozzle is also provided with a curved slot 12 arranged concentric or in circular alignment with a series of ports 9 50 and with a curved slot 12^a arranged concentric or in circular alignment with the arcuate series of ports 9^a and the said slots 12 and 12^a are adapted to be brought successively into register with the outlet of the air passage 10 for destroying the vacuum during portions of the revolution of the pull off nozzle. One end of the curved slot 12 is spaced from the arcuate series of ports 9 and one end of the curved slot 12^a is spaced 55 from the arcuate series of ports 9^a to provide intervening imperforate surfaces 13 and 13^a which are adapted to close or cover the outlet of the passage 10 during a portion of each revolution of the pull off nozzle to 60 cut off the suction from the nozzle and

throw the full suction on one or more winding arms 14 which first engage the uppermost sheet 5 of the stack and then leave the same and move the edge of the sheet backwardly as illustrated in dotted lines in Fig. 70 4 of the drawings to produce an undulation in the sheet for winding the same similar to the winding of a sheet by hand to separate the sheet from the rest of the stack as explained in the aforesaid applications. The winding arms 14 are suitably mounted on a transverse pivot shaft 15 journaled in suitable bearings in the sides of the frame 3 of the machine and carrying a cam actuated lever 16 and a valve operating arm 17. The winding arm is approximately L-shaped and is secured at one end to the shaft 15 and is provided with a hollow tubular portion 18. The hollow tubular portion 18 forms a passage for the air downwardly and provides at its lower end a suction mouth which is adapted to engage the uppermost sheet of the same at the forward edge thereof to lift and wind the same as before explained. The winding arm is interiorly threaded at 80 the upper end of the passage 19 for the reception of a threaded nipple 20 which forms a hose connection.

The cam actuated lever 16 which is located at one side of the machine adjacent to the frame is provided at its outer or cam engaging end with a roll 22 which is mounted on a suitable journal 23 consisting of a bolt having a smooth portion to receive the roll and threaded portion to engage a 90 threaded opening 16^a in the cam actuated lever 16. The bolt which forms the journal 23 is provided with a lock nut 23^a and is removable and reversible to enable the roll 22 to be arranged at either side of the cam 100 actuated lever arm 16 to cooperate with either a single cam 24 or a double cam 24^a. The cam actuated lever arm 16 is located opposite the space between the cams 24 and 24^a and by reversing the roll 22 and changing the same from the outer side of the lever arm 16 to the inner side of the same the roll is carried from operative position with relation to the single cam 24 to its operative position with relation to the double cam 24^a. 110 When the machine is arranged for feeding a single sheet during each revolution of the nozzle the roll 22 rests upon the cam 24 at the center of the top as clearly illustrated in Fig. 4 of the drawing and as the winding arms 14 and the arms 16 and 17 are rigidly secured to the pivot shaft 15 by screws or other suitable fastening devices there is sufficient weight to cause the roll to press firmly against the cam whereby the cam actuated lever arm will move in accordance with the contour of the cam. The cam 24 is provided with a cutout portion 25 forming a cam face for actuating the arm 16 for lowering and raising the winding arms to carry 120 125 130 135

the same to the stack and to lift the uppermost sheet thereof and wind the same. The remaining portion of the peripheral surface of the cam 24 is circular and maintains the winding arm in an elevated position while the pull off nozzle is operated to pull off the sheet and carry the same to the pull off roll and rubber covered rolls. The double cam 24^a is provided with two cutout portions or recesses 25^a located at diametrically opposite portions of the double cam 24^a and adapted to produce two operations of the cam actuated arm 16 for raising and lowering the winding arms and for operating the valve 15 operating arms 17 twice during each revolution of the suction nozzle. The portions of the peripheral surface of the double cam is circular between the recesses 25^a to maintain the winding arms in an elevated position 20 while the pull off nozzle is operated to pull off a sheet and carry the same to the pull off roll and the rubber covered spools.

The arm 17 which operates the air valve is located exteriorly of the frame of the machine at the opposite side of that at which the cam actuated lever arm 16 is arranged and is approximately L-shaped and extends downwardly from the pivot shaft 15 and longitudinally of the side of the machine to a point adjacent an air valve 26 provided with a cutoff piston or movable valve member 27. The air valve consists of a body provided with a main longitudinal passage 28 and a smaller longitudinal passage 29. The valve is preferably arranged in a vertical position as shown and the passages 28 and 29 are vertical. The lower end of the vertical longitudinal passage 28 is connected with a main suction hose by a nipple or hose connection 31 which is threaded into the lower end of the passage 28 and a suitable hose connection or nipple 32 is threaded into the upper end of the main longitudinal passage 28 for the attachment of a hose 33 which is connected with the suction nozzle 1 through the passage of the air arm 11. The smaller longitudinal passage 29 has threaded into its upper end a nipple or hose connection 34 which receives a hose 35 extending to one of the winding arms. The hose 36 extends to the other winding arm and is connected by an L-shaped nipple or hose connector 37 which is threaded at one end into a transverse passage or bore 38 extending into the body of the air valve from one face thereof and intersecting the longitudinal passages 28 and 29. The transverse air passage 38 communicates with the longitudinal passage 29 and also with the main longitudinal passage 28. When the suction is on the winding arms through the transverse passage 38 the suction is cut off from the pull off nozzle by the imperforate surface between the arcuate series of ports 9 and the curved slot 12 so that the entire

suction will be on the winding arms. The operation is the same when either the single cam or the double cam is used with the exception that there are two operations of the air valve during each revolution of the suction nozzle when the double cam is in use. The suction as explained in the aforesaid applications may be made either heavy or light to suit the character of the stock being fed by the machine and is regulated by means of pepper box dials 39 and 40 each having a plurality of apertures 41 of different sizes adapted to be brought into register respectively with transverse vent passages 42 and 43 extending from the exterior of the longitudinal passages 28 and 29. Each pepper box dial is mounted on a pivot 44 which passes through the central opening 45 in the perforated disk which has disposed on it a coiled spring 46 for pressing the disk against the body of the air valve. The body of the air valve is provided at the vents 42 and 43 with smooth flat circular faces 47 and 48 to cooperate with the pepper box dials.

The cut off piston or movable valve member 27 which is cylindrical is mounted in the lower portion of the bore or passage 29 and is movable from the position illustrated in full lines in Fig. 8 of the drawings to the dotted line 49 in said figure to close the passages leading to the winding arms for cutting off the vacuum from the winding arms to throw the full force of the vacuum into the hose extending from the main longitudinal passage of the air valve to the pull off nozzle. The cut off passage is reciprocated in the valve chamber passage 29 of the air valve by the arm 17.

The air arm is provided with a smooth flat bearing surface to fit against the pull off nozzle and this surface is formed by a wood bushing 50 as explained in the said applications. The bushing 50 is mounted on a metal sleeve 51 carrying a nipple or hose connection 52 to which is connected the hose 33 extending from the nipple 32 of the air valve to the air arm. The sleeve 51 is provided with a stem 53 and a coiled spring 54 is arranged on the stem at a recess 55 into which the bearing arm is interposed between one wall of the recess and the bearing arm for yieldably maintaining the wood bushing in contact with the pull off nozzle. The air arm 11 is fixed by a screw or other suitable fastening device to a transverse rod or shaft 56 on which are mounted the arms 57 which carry the rubber covered spools 7. The air valve is provided with a throttle valve consisting of a port or opening 68 and a pivoted hand operated lever 69 pivoted intermediate of its ends on a pin or screw 70 and maintained in proper frictional contact with the valve body by a coiled spring 71. The valve lever 69 is adapted to be operated by hand 130

for destroying and restoring the vacuum so that the feeding of the machine may be stopped and started as required. The main suction hose 30 is connected with a rotary vacuum pump 72.

The stack of sheets is arranged upon a vertically movable table 79 constructed substantially the same as that shown in Patent No. 1,546,184 granted to me July 14, 1925 with the exception that the mechanism for elevating the table automatically is operated by an elevating lever 80 fulcrumed intermediate of its ends at 81 and pivotally connected at one end with a vertically movable bar 82 of the ratchet mechanism and at its upper end with a link or connecting rod 89' with a wrist pin 90 of a pulley 88' mounted on a shaft 2. The rotary suction fan 72 is driven by an electric motor 83 which is connected with a rotary suction pump by a belt 84 and pulleys 85 and 86 but any other suitable means may of course be employed for transmitting motion from the electric motor to the rotary suction fan which as explained in the aforesaid patent discharges into a tank 87 for supplying the compressed air to be discharged upon the stack as fully explained in said patent.

Referring to Fig. 4 of the drawings which shows the winding arms down ready to pick up the sheet, when the cam is in this position the arm 17 has caused the cut off piston to descend and the vacuum is on the winding arms owing to the fact that the rotary suction disk or nozzle has rotated beyond the end of the curved slot 12 and the imperforate or dead surface 13 closes the outlet or port of the wood bushing. As the winding arms lift the sheet and wind it the cut off valve closes cutting off the suction from the winding arm and transmitting it to the rotary suction nozzle, as the first port has rotated into register with the port or outlet of the wood bushing and the sheet is now pulled off the pile by the rotary movement of the suction disk or nozzle and a successive engagement of the suction mouths with the sheets. As the suction disk or nozzle continues to rotate the curved slot 12 comes into register with the port or opening in the wood bushing, thereby destroying the vacuum on the air valve and the suction nozzle and the winding arms. This operation takes place once when the single cam is arranged for actuating the arms 16 and when the double cam is arranged for operating the cam actuated arm 16. The rotary suction nozzle or disk continues its rotary movement and the rotation of the cam lowers the winding arms and when they are just at their lowest point the curved slot passes beyond the port or opening of the wood bushing and the vacuum is restored ready to pick up the next sheet. When the double cam is in use the foregoing operations occur twice

during each complete revolution of the rotary suction nozzle and when the single cam is in use the closure plate is arranged to uncover the vent ports of the suction mouths 4^a to provide only one effective set or series 70 of suction mouths.

What is claimed is:—

1. A rotary feeder including a continuously rotating pull off suction nozzle provided at its periphery with two arcuate sets of suction mouths having air ports, one set of suction mouths being provided with vent outlets, means for covering and uncovering the outlets for feeding either one or two sheets during each revolution of the 80 nozzle, and suction means with which the air ports are adapted to successively register.

2. A rotary feeder including a continuously rotating pull off suction nozzle provided at its periphery with two arcuate sets of suction mouths having lateral air ports located at one side of the nozzle, one set of suction mouths being also provided with vent outlets located at the other side of the nozzle, means for covering and uncovering the vent outlets for feeding either one or two sheets during each revolution of the nozzle, and suction means with which the air ports are adapted to successively register.

3. A rotary feeder including a continuously rotating pull off suction nozzle provided at its periphery with two arcuate sets of suction mouths having air ports, one set of suction mouths being provided with vent outlets, a closure plate covering the 100 vent outlets and movable therefrom to render one set of suction mouths inoperative, and suction means with which the air ports are adapted to successively register.

4. A rotary feeder including a continuously rotating pull off suction nozzle provided at its periphery with two arcuate sets of suction mouths having lateral air ports located at one side of the nozzle, one set of suction mouths being also provided with vent outlets located at the other side of the nozzle, a closure plate covering the vent outlets and movable therefrom to render one set of suction mouths inoperative, and suction means with which the air ports are adapted to successively register.

5. A rotary feeder including a continuously rotating pull off suction nozzle provided at its periphery with two arcuate sets of suction mouths having air ports, one set of suction mouths being provided with vent outlets, means for covering and uncovering the outlets for feeding either one or two sheets during each revolution of the nozzle, suction means with which the air ports are adapted to successively register, oscillating means for picking up a sheet from a stack and delivering it to the pull off nozzle, single and double cams rotating with the pull off nozzle, and cam actuated means con- 130

nected with the said oscillating means and adapted to be engaged with either of the cams for operation by the same.

6. A rotary feeder including a continuously rotating pull off suction nozzle provided at its periphery with two arcuate sets of suction mouths having lateral air ports located at one side of the nozzle, one set of suction mouths being also provided with vent outlets located at the other side of the nozzle, means for covering and uncovering the vent outlets for feeding either one or two sheets during each revolution of the nozzle, suction means with which the air ports are adapted to successively register, oscillating means for picking up a sheet from a stack and delivering it to the pull off nozzle, single and double cams rotating with the pull off nozzle, and cam actuated means connected with the said oscillating means and adapted to be engaged with either of the cams for operation by the same.

7. A rotary feeder including a continuously rotating pull off suction nozzle provided at its periphery with two arcuate sets of suction mouths having air ports, one set of suction mouths being provided with vent outlets, a closure plate covering the vent outlets and movable therefrom to render one set of suction mouths inoperative, suction means with which the air ports are adapted to successively register, oscillating means for picking up a sheet from a stack and delivering it to the pull off nozzle, single and double cams rotating with the pull off nozzle, and cam actuated means connected with the said oscillating means and adapted to be engaged with either of the cams for operation by the same.

8. A rotary feeder including a continuously rotating pull off suction nozzle provided at its periphery with two arcuate sets of suction mouths having lateral air ports located at one side of the nozzle, one set of suction mouths being also provided with vent outlets located at the other side of the nozzle, a closure plate covering the vent outlets and movable therefrom to render one set of suction mouths inoperative, suction means with which the air ports are adapted to successively register, oscillating means for picking up a sheet from a stack and delivering it to the pull off nozzle, single and double cams rotating with the pull off nozzle, and cam actuated means connected with the said oscillating means and adapted to be engaged with either of the cams for operation by the same.

9. A rotary feeder including a continuously rotating suction nozzle provided at its periphery with two arcuate sets of suction mouths having air ports, one set of suction mouths being provided with vent outlets, means for covering and uncovering the vent outlets for feeding either one or two sheets

during each revolution of the nozzle, suction means with which the air ports are adapted to successively register, oscillating means for picking up a sheet from a stack and delivering it to the pull off nozzle, single and double cams rotating with the pull off nozzle, and an oscillating arm connected with the said oscillating means and adapted to be engaged with either of the cams for operation thereby.

10. A rotary feeder including a continuously rotating suction nozzle provided at its periphery with two arcuate sets of suction mouths having air ports, one set of suction mouths being provided with vent outlets, means for covering and uncovering the vent outlets for feeding either one or two sheets during each revolution of the nozzle, suction means with which the air ports are adapted to successively register, oscillating means for picking up a sheet from a stack and delivering it to the pull off nozzle, single and double cams spaced apart and rotating with the pull off nozzle, and a cam actuated arm connected with the oscillating means and located at the space between the cams and having reversible means adapted to be arranged to be engaged by either of the single or double cams.

11. A rotary feeder including a continuously rotating suction nozzle provided at its periphery with two arcuate sets of suction mouths having air ports, one set of suction mouths being provided with vent outlets, means for covering and uncovering the vent outlets for feeding either one or two sheets during each revolution of the nozzle, suction means with which the air ports are adapted to successively register, oscillating means for picking up a sheet from a stack and delivering it to the pull off nozzle, single and double cams spaced apart and rotating with the pull off nozzle, a cam actuated arm connected with the oscillating means and located at the space between the said cams and provided with a reversible lateral projecting roll adapted to be arranged at either side of the arm for engaging with either of the cams.

12. A rotary feeder including a continuously rotating shaft, a pull off suction nozzle mounted on and rotating with the shaft and provided at its periphery with two arcuate sets of suction mouths having air ports, one set of suction mouths being also provided with vent outlets, means for covering and uncovering the vent outlets, single and double cams spaced apart and mounted upon the said shaft and rotating with the pull off nozzle, oscillating means for picking up a sheet from a stack and delivering it to the pull off nozzle, and an oscillating arm connected with the oscillating means and located at the space between the said cams and provided with a reversible later-

ally projecting roll adapted to be arranged to engage with either of the said cams.

13. A rotary feeder including a continuously rotating shaft, a pull off suction nozzle mounted on the shaft and rotating therewith and provided at its periphery with two arcuate sets of suction mouths having air ports, one set of suction mouths being also provided with vent outlets, means for covering the vent outlets, a double cam mounted on the said shaft and rotating with the suction nozzle, oscillating means for picking up a sheet from a stack and delivering it to the pull off nozzle, and means operated by the 10 double cam for actuating the said oscillating means.

14. A rotary feeder including a continuously rotating shaft, a pull off suction nozzle mounted on the shaft and rotating therewith and provided at its periphery with two arcuate sets of suction mouths having air ports, one set of suction mouths being also provided with vent outlets, means for covering the vent outlets, a double cam mounted on the said shaft and rotating with the suction nozzle, oscillating means for picking up a sheet from a stack and delivering it to the pull off nozzle, an oscillating arm connected with the said oscillating means and operated by the said double cam. 20 25 30

In testimony whereof I affix my signature.

LESTER KYLE ALDRICH.
